CLAIM

The ornamental design for a toothbrush holder with removable sterilizing receptacles, as shown and described.

DESCRIPTION

FIG. 1 is an exploded top, front, and right side perspective view of a toothbrush holder with removable sterilizing receptacles showing our new design;

FIG. 2 is a top plan view thereof;

FIG. 3 is a bottom plan view thereof;

FIG. 4 is a right side elevational view thereof, with the left side being a mirror image of that shown and the broken-line disclosure of a toothbrush descending into the receptacle being for illustrative purposes only and forming no part of the claimed design;

FIG. 5 is a rear elevational view thereof; and,

FIG. 6 is a front elevational view thereof.

FIG. 3

FIG. 4

FIG. 5

FIG. 6
